UNITED STATES PATENT OFFICE

ALBERT MEEHAN AND EDWIN GRAY, OF NEW YORK, N. Y.

GLOVE STRETCHING DEVICE

Application filed January 29, 1930. Serial No. 424,195.

This invention relates to improvements in glove stretching devices, and it consists in the novel features, which are hereinafter described.

5 One of the objects of my improvement is to produce a perfected glove stretching device, having a substantially uniform stretching action simultaneously through the hand portion and the finger portions of the device.

10 Another object of my invention is to produce a device of the above class, in which the stretching of the glove is done in a direction substantially at right angles to the plane of the glove throughout the extent of the glove 15 by a motion of the expanding device in a plane parallel to the plane of the glove.

A further object of my invention is to produce a perfected glove stretching device, of 20 which the parts are adapted to be made by methods of quantity production, thereby reducing the cost of the device.

A still other object of my invention is to have the above device effective, simple and durable.

25 Other objects and advantages will herein-after appear.

I attain these objects by the glove stretching device, illustrated in the accompanying drawings, or by any mechanical equivalent 30 or obvious modification of the same.

In the drawings.

Fig. 1 is a plan view from the outside of my glove stretching device for a left hand glove, with the palm part placed to face upwardly;

35 Fig. 2 is an edge-view of my glove stretching device looking from left to right in Fig. 1, showing the component parts of my device in closed position and the device as un-expanded;

40 Fig. 3 is a plan view from the interior of my glove stretching device, which is shown in Figs. 1 and 2, of the part of the said device, which is contiguous to the back part of the glove;

45 Fig. 4 is a plan view of the interiorly positioned expanding member of my glove stretching device, which is hereinafter described;

50 Fig. 5 is an edge view, looking from right

to left in Fig. 4, of the above interiorly positioned expanding member;

Fig. 6 is an end view of said member on the line 6—6 of Fig. 4, looking in the direction of the arrows;

Fig. 7 is a section on the line 7—7 of Fig. 3 of the part of my glove stretching device, which is shown in Fig. 3;

Fig. 8 is an edge view, partly in section, which is similar to Fig. 2, but showing the 60 component parts of my device in open position and the device as expanded.

Like reference character refer to like parts throughout the several views:

11 designates a substantially rigid palm plate and 12 a substantially rigid back plate of my glove stretching device; said palm plate 11 is shown as having secured thereto a substantially rigid front thumb plate 13, and said back plate 12 is shown as having secured thereto a substantially rigid rear thumb plate 14.

Hand portions 11^a and 12^a and finger portions 15 and 16 are shown on said plates 11 and 12 respectively, integrally therewith.

Inwardly extending tapering depressions 17 and 18 are shown as formed in the hand portions 11^a and 12^a of said plates 11 and 12 respectively, and similar depressions 19 and 20 are formed in said finger portions 15 and 16 respectively; said thumb plates 13 and 14 also have formed therein inwardly extending tapering depressions 21 and 22 respectively.

Said depressions 17, 18, 19, 20, 21 and 22 in the outer sides of the hand portions 11^a and 12^a of said plates 11 and 12, said thumb parts 13 and 14 and said finger portions 15 and 16 manifest themselves on the inner sides of said plates, portions and parts as tapered 90 projections or elevations, which serve to stiffen said plates, portions and parts and to contact with similar but oppositely positioned double projections or elevations 23, 24 and 25 respectively of the hand counterpart, 95 finger counterpart and thumb counterpart on an interiorly positioned expanding member 26, which has said projections 23, 24 and 25 preferably made integrally therewith, and said projections 24 and 25 are joined thereto 100

by means of extensions 24^a and 25^a respectively, as shown in Figs. 4 and 5.

Said elevations on said plates, portions and parts are so disposed and inclined as to render the successive positions of said plates, portions and parts during the transverse motion thereof, which is hereinafter described, substantially parallel to each other.

Said plates 11 and 12 are shown as expansively connected to each other by means of one or more pins 27, which may be secured each at one end thereof to one of said plates, such as plate 12 in Fig. 7, and movably connected each to a resilient socket 28 on the other of said plates, such a plate 11 in Fig. 7; each of said pins 27 has thereon a head 29, to be intercepted by the inner end of said socket 28 after said plates 11 and 12 have been displaced with relation to each other to the utmost desirable extent, thereby opposing, but not entirely preventing the separation of said plates 11 and 12 from each other.

Said thumb plates 13 and 14 may be permanently secured to said plates 11 and 12 respectively, as if by rivets 30, as shown in Fig. 1, whereby said thumb-plates 13 and 14 are caused to move with said plates 11 and 12 during the operation of expanding and collapsing my glove stretching device by means of said member 26 and the projections 23, 24 and 25 thereon in cooperations with said parts 17, 18, 19, 20, 21 and 22 on the inner sides of said plates 11, 12, 13 and 14 and said finger portions 15 and 16.

To move said member 26 and the parts thereon with relation to said plates 11 and 12 and the parts on the latter I provide a connecting rod 31, which passes through an opening 31^a in said projection 23 and is pivotally connected at one end thereof by means of a pin 32 to said member 26 at said double projection 23, as shown in Figs. 4 and 5, and at the other end thereof by means of a pin 33 to a lever 34, which is pivotally connected by means of a pair of pins 35 to said plates 11 and 12, as shown in Figs. 1 and 3, in which said rod 31, pins 32 and 33 and lever 34 are shown by broken lines; said pins 35 may be secured at their outer ends to said plates 11 and 12, and their inner ends may then be both pivotally and slidably connected to said lever 34 in an opening 35^a therein.

In Fig. 3 two positions of the last mentioned parts are shown in broken lines.

Said plates 11 and 12 and said portions 15 and 16 have thereon each on the sides thereof inwardly extending flanges 36, and said thumb plates 13 and 14 have thereon each on the sides thereof inwardly extending flanges 37, as shown in Fig. 7.

Said double projections 24 and 25 of said member 26 extend laterally substantially to contact with said flanges 36 and 37, as shown in broken lines in Figs. 1 and 3, thereby

keeping said plates 11 and 12 in lateral alignment with each other.

Said thumb plate 14 is secured to said back plate 12 by means of a bracket 38, which is made integral with said thumb plate 14 and is shown in Figs. 3 and 7, and said extension 25^a on said member 26 slides in an opening 39 in said palm plate 11, which is shown in Fig. 1, when said member 26 is moved with relation to said plates 11 and 12 lengthwise thereof for expanding or contracting the space therebetween in a direction transversely thereto, thereby respectively expanding or releasing a glove, enveloping the same.

Said inner elevations 17, 18, 19, 20, 21 and 22 and said double projections 23, 24 and 25 are made of a size and inclination to keep the motion of all parts on said plates 11 and 12 when moving said member 26 with relation thereto substantially equal in extent and in a direction substantially at right angles to the plane thereof, thereby rendering the successive positions of said parts parallel to each other.

Said plates 11 and 12 and the parts thereon as well as said member 26 and the parts thereon are preferably of a shape allowing them to be produced by means of punch and die work, thereby providing an inexpensive way of manufacturing the same.

Said flanges 36 on said plates 11 and 12 have therein a gap 40 at one end thereof, as shown in dotted lines in Fig. 2, to permit the free end of said lever 34 to extend therethrough when said plates 11 and 12 and said member 26 are in the relative positions as shown in Fig. 1, when my glove stretching device is contracted.

Many changes may be made in the details of my glove stretching device without departing from the main scope of my invention, and parts of my invention may be used without other parts.

I do not, therefore, restrict myself to the details as shown in the drawings; but I intend to include also all mechanical equivalents and obvious modifications of the same within the scope of my invention.

I claim as my invention, and desire to secure by Letters Patent:

1. In a glove stretching device a palm plate, a back plate, finger portions and thumb parts on said plates, an expanding member, enclosed therebetween, inwardly extending elevations on the inner faces of one or more of said plates, said portions and said parts and projections on said member, to cooperate with said elevations to move said plates in opposite directions with relation to each other and in a direction transversely to the planes thereof, said member with said projections thereon being formed substantially of an integral sheet of material wrought to the required shape.

2. In a glove stretching device a palm plate,

- a back plate, finger portions on said plates, an expanding member, enclosed therebetween, inwardly extending elevations on the inner faces of one or more of said plates and said 5 portions and projections on said member, to cooperate with said elevations to move said plates in opposite directions with relation to each other and in a direction transversely to the planes thereof, said member with said 10 projections thereon being formed substantially of an integral sheet of material, wrought to the required shape.
3. In a glove stretching device a palm plate, a back plate, finger portions on said plates, an expanding member, enclosed therebetween, inwardly extending elevations on the inner faces of each of said plates and said portions and double projections on said member, to 15 cooperate with said elevations on opposite sides thereof to move said plates in opposite directions with relation to each other and in a direction transversely to the planes thereof, said member with said projections thereon being formed substantially of an integral 20 sheet of material, wrought to the required shape.
4. In a glove stretching device a palm plate, a back plate, finger portions and thumb parts on said plates, said thumb parts comprising 25 a front thumb plate, secured to said palm plate, and a rear thumb plate with a bracket, made integrally therewith and secured thereby to said back plate, an expanding member, enclosed between said plates, inwardly extending elevations on the inner faces of one 30 or more of said plates, said portions and said parts and projections on said member, to cooperate with said elevations to move said plates in opposite directions with relation to each other and in a direction transversely to the planes thereof.
5. In a glove stretching device a palm plate, a back plate, finger portions and thumb parts on each of said plates, an expanding member, enclosed therebetween, inwardly extending elevations on the inner faces of one or more 35 of said plates, said portions and said parts, projections on said member, to cooperate with said elevations to move said plates in opposite directions with relation to each other and in a direction transversely to the planes thereof, and a means for keeping said plates in lateral alignment with each other.
6. In a glove stretching device a palm plate, a back plate, finger portions and thumb parts on each of said plates, an expanding member, enclosed therebetween, inwardly extending elevations on the inner faces of one or more 40 of said plates, said portions and said parts, inwardly extending flanges on the sides of said portions and said parts and projections on said member, to cooperate with said elevations to move said plates in opposite directions with relation to each other and in a direction transversely to the planes thereof,
- the projections on said member, which are enclosed between said portions and between said parts, extending laterally substantially to contact with the flanges on the sides thereof, thereby keeping said plates in lateral alignment with each other.
7. In a glove stretching device a palm plate, a back plate, finger portions and thumb parts on said plates, an expanding member, enclosed therebetween, inwardly extending elevations on the inner faces of one or more of said plates, said portions and said parts, projections on said member, to cooperate with said elevations to move said plates in opposite directions with relation to each other and in a direction transversely to the planes thereof, and a means for expansively connecting said plates to each other.
8. In a glove stretching device a palm plate, a back plate, finger portions and thumb parts on said plates, an expanding member, enclosed therebetween, inwardly extending elevations on the inner faces of one or more of said plates, said portions and said parts, projections on said member, to cooperate with said elevations to move said plates in opposite directions with relation to each other and in a direction transversely to the planes thereof and a means for expansively connecting said plates to each other, said means comprising one or more pins, secured to one of said plates, and one or more resilient sockets on the other of said plates, movably connected to said pins.
9. In a glove stretching device a palm plate, a back plate, hand portions, finger portions and thumb parts on said plates, an expanding member, enclosed therebetween, inwardly extending elevations on the inner faces of one or more of the hand portions of said plates, one or more of said finger portions and one or more of said thumb parts and projections on said member, to cooperate with said elevations to move said plates in opposite directions with relation to each other and in a direction transversely to the planes thereof, said plates with said portions and parts thereof being relatively thin and said elevations thereon serving also to stiffen the same, thereby increasing the rigidity thereof.
10. In a glove stretching device a palm plate, a back plate, hand portions, finger portions and thumb parts on said plates, an expanding member, enclosed therebetween, inwardly extending elevations on the inner faces of one or more of the hand portions of said plates, one or more of said finger portions and one or more of said thumb parts and projections on said member, to cooperate with said elevations to move said plates in opposite directions with relation to each other and in a direction transversely to the planes thereof, the elevations on said hand portions, said finger portions and said parts with the corresponding projections on said member being

so disposed and inclined as to render the successive positions of said plates and portions during said transverse motion of said plates substantially parallel to each other.

5 Signed at New York in the county of New York and State of New York this 31st day of December, A. D. 1929.

ALBERT MEEHAN.
EDWIN GRAY.
